L. M. LARSEN

HUMIDOR

Filed Aug. 29, 1923

Inventor
Lawrence M. Larsen

Daniel F. Grammas.

Attorney

UNITED STATES PATENT OFFICE.

LAWRENCE MARTIN LARSEN, OF CHICAGO, ILLINOIS.

HUMIDOR.

Application filed August 29, 1923. Serial No. 659,927.

To all whom it may concern:

Be it known that I, LAWRENCE MARTIN LARSEN, a citizen of the United States, residing at Chicago, in the county of Cook and State of Illinois, have invented new and useful Improvements in Humidors, of which the following is a specification.

The invention relates to devices for keeping tobacco moist in containers.

10 An object of the invention is to provide a humidor that can be easily attached to a tobacco receptacle or the like.

15 It is a further object of the invention to provide a humidor that will be simple of construction and inexpensive of manufacture and adapted to be utilized as an advertising novelty.

Other objects will become apparent upon a perusal of the specification.

20 Figure 1 is a fragmental perspective view of a tobacco receptacle showing a preferred form of the invention in place.

Figure 2 is a fragmental cross-section taken through the device and tobacco receptacle shown at an enlarged scale.

Figure 3 is a perspective view with the end cut away of the preferred form of the invention shown at an enlarged scale.

Figure 4 is a plan view of a modified form 30 of the invention shown attached to a tobacco receptacle.

Figure 5 is a cross-section taken on line 5—5 of Figure 4.

Figure 6 is a plan view, of the invention 35 shown attached to the tobacco receptacle.

Figure 7 is a cross-section taken on line 7—7 of Figure 6.

40 My device in its preferred form as illustrated in Figures 1, 2 and 3 has an outer casing 10 formed of one piece of metal or other substantial material.

45 A resilient clip 13 is securely fastened transversely on the center of the upper wall 11 of the outer casing, in which apertures 12 are provided. One end of the clip projects beyond the side of the casing, and is bent slightly upward as at 14. The other end of the clip is bent downwardly forming a corrugated portion 15; the extreme end 16 50 is bent downwardly again for a short distance, thus providing a yielding connection for engaging a receptacle.

A closure 17 of the same shape as the outer casing but slightly smaller and having apertures 18 in its bottom wall is yieldingly yet securely fitted in said casing and is provided with a handle 19 for removing the device from the receptacle. 55

The space between the casing and the closure is filled with an absorbent material, 60 preferably asbestos.

To put the device in position in the cover of the receptacle, part 16 is placed over a hinge 21 (Fig. 2), and the device is then pressed inwardly and upwardly until the end 65 14 engages the upper edge of the receptacle. The resiliency of the corrugated element then holds the humidor in place.

The modified form shown in Figures 6 and 7 has an outer casing 23 formed integral with the receptacle, and its inner closure 22 is formed to securely engage the casing 23, and is provided with apertures 24 in its bottom wall, thus permitting evaporating water from the absorbent material 20 to 70 escape and imbue the tobacco in the receptacle, thus keeping its contents moist. 75

Another modified form is shown in Figures 4 and 5. In this form an outer casing 25 is securely riveted to a receptacle and an inner closure 26 is detachably mounted therein, and is provided with apertures 27. It is not desired to limit the invention illustrated and described herein except where limitations appear in the appended claim. 80 85

I claim:

In combination with a tobacco can and cover, a humidor comprising a casing having semicircular ends, and provided with apertures in its top wall, a resilient clip 90 secured transversely on said casing, a corrugated end on said clip adapted to engage with the tobacco can cover, whereby said humidor is held yieldingly in slanting engagement therewith. 95

In testimony whereof I affix my signature in the presence of two witnesses at 7 South Dearborn Street, Chicago, Illinois.

LAWRENCE MARTIN LARSEN.

Witnesses:

DANIEL A. BRENNEN,
BERTHA FELDMAN.
